Primary Examiner — Richard E Chilcot(74) *Attorney, Agent, or Firm* — Fish & Richardson P.C.(57) **CLAIM**

The ornamental design for mobile accessory with cameras, as shown and described.

DESCRIPTION

FIG. 1 is a front perspective view of the mobile accessory with cameras.

FIG. 2 is a front view thereof.

FIG. 3 is a back perspective view thereof.

FIG. 4 is a left side view thereof.

FIG. 5 is a right side view thereof.

FIG. 6 is a top view thereof.

FIG. 7 is a bottom view thereof; and,

FIG. 8 is a bottom perspective view thereof.

In some implementations, the mobile accessory with cameras includes radial segments that intersect with a central rounded portion, as illustrated in FIGS. 1, 6, 7.

The broken lines illustrate portions of the mobile accessory with cameras that form no part of the claimed design.

1 Claim, 5 Drawing Sheets
